UNITED STATES PATENT OFFICE

FREDERICK C. LANGENBERG, OF NEW YORK, N. Y., ASSIGNOR TO UNITED STATES CAST IRON PIPE & FOUNDRY COMPANY, OF BURLINGTON, NEW JERSEY, A CORPORATION OF NEW JERSEY

METHOD AND APPARATUS FOR IMPROVING THE TEXTURE OF HOLLOW METAL BODIES

Application filed December 29, 1928. Serial No. 329,208.

My invention relates to a method whereby the form of hollow metal bodies can be rapidly and economically changed and at the same time the internal structure of the steel or other metal of the body is improved by subjecting such bodies to external fluid pressure whereby the metal bodies are simultaneously radially contracted and longitudinally elongated and whereby the structure of such bodies is so changed as to materially increase the strength and other useful qualities, such as resistance to wear, of the metal. My invention is especially applicable to hollow steel bodies of a generally cylindrical form and has been found of a special value as applied in the manufacture of steel molds for the centrifugal casting of tubes. The application of my invention, however, to the manufacture of centrifugal steel molds and particularly to the manufacture of new molds from used steel molds which have become useless by reason of the roughening of their inner surfaces forms the subject matter of a separate application for Letters Patent, filed December 29, 1928 Serial No. 329,189, for which Letters Patent No. 1,753,747 were granted April 8, 1930, my present application being intended to cover broadly the application of my invention in the manufacture of any metal structures and the essential features of an apparatus such as must be provided for the practice of my process.

The nature of my improvements will be best understood as described in connection with the drawings, in which

Figure 1 is a sectional elevation of an apparatus designed for the application of my process, said view showing a tubular steel mold located in the apparatus in position to be operated upon a mandrel upon which the blank is to be compacted, packing rings located to confine the fluid under pressure and a special arrangement by means of which the fluid under pressure is made to exert both

a contracting and elongating stress upon the mold or blank, the form of which is to be changed.

Figure 2 shows a modification of the apparatus shown at the left hand end of Figure 1, in which the packing is so held that it does not subject the mold or blank to a direct longitudinal stress, and

Figure 3 is a sectional elevation showing a modification of the apparatus in which the mold or blank here shown as of cylindrical form throughout is permitted to expand longitudinally in both directions.

Referring first to Figure 1, A indicates the container which must, of course, be of great strength to withstand the pressure to which it is subjected. A¹ indicates the inside of the container; a¹ an enlargement at the right hand end of the container adapted to receive the bell end of a pipe mold and A² a conduit passage for fluid under pressure. B is an end plate firmly secured to the right hand end of the container. C is a mandrel which is located inside of the mold or blank to be operated on and upon which said mold or blank is compacted, C¹ indicating an enlarged end of this mandrel which, as shown, fits in the outer portion of the bell end of the mold under treatment. D indicates the mold or blank, here shown as an already formed centrifugal steel mold which, by my process, is to be radially contracted and simultaneously longitudinally expanded by the fluid pressure to which it is subjected. D¹ indicates the bell end of this mold and D², D², indicates circumferential slots formed at the spigot end of the mold, such as are usually provided to receive packing rings when the mold is in use. D³ indicates the inner surface of the mold which, in cases where the blank under treatment is a used mold, will become cracked and roughened. E indicates a packing ring fitted between the enlarged portion a¹ of the container and the bell end of the mold, the packing ring being shown as

resting against a retaining ring F and as having a wide spreader, as indicated at G, inserted in the U-shaped packing ring. H, H, indicate rings which are located in the circumferential slots D². I, a block resting against the rear ring H and F¹ a block resting against the forward ring H and against the end of the ring I and F¹ is a packing ring resting against the block or ring F¹.

- 10 In operation the blank or mold is placed in the container as indicated with the mandrel C in position as shown and with the packing rings F and F¹ fitted between the inside of the container and the outside of the blank 15 or mold and supported in position by the devices which I have described; the parts being assembled, fluid under pressure is admitted through the port A² and acting on the outside of the mold or blank radially contracts said blank and at the same time longitudinally elongates the blank and, in the construction of Figure 1, this elongation of the blank which will take place by the mere pressure exerted on the outside of the blank 25 when it is radially contracted is facilitated by the direct application of the pressure through the packing ring F¹ and the supports of said packing ring to the spigot end of the mold or blank. Care must be taken, 30 however, that the area of the packing ring F¹ exposed to the fluid pressure is not so great as to exert an undue longitudinal stress on the blank as, otherwise, there may be a tendency to tear the blank in two. The pressure should be only such as will facilitate 35 and aid in the elongation of the blank.

The effect of the radial contraction and longitudinal expansion of the blank is both to compact and change the form of the crystals or component elements of the metal in such a way as to materially increase its density, strength and hardness.

Referring to the modification shown in Figure 2: in the construction here indicated, the container is provided with an end plate J, against which abuts a follower, indicated at K, on which again rests the ring indicated at F³ which directly supports the packing ring indicated at E². With this construction the packing ring E² exerts no longitudinal stretching force upon the mold or blank, a longitudinal expansion of which takes place purely by the circumferentially applied fluid pressure.

55 In the modification shown in Figure 3, the blank indicated at D, D, is of cylindrical form and followers K and K¹ are provided at both ends of the container to support the packing indicated at E and E¹. By means of this construction the fluid pressure applied to the blank not only contracts the blank upon the mandrel but effects a longitudinal expansion of the blank in both directions.

60 It will be understood, of course, that many of the advantages of my invention can be

availed of by contracting a blank to a certain definite extent regulated by the amount of fluid admitted to the container and without the use of a mandrel although obviously the mandrel is a highly desirable feature of the construction, both in limiting the contraction of the blank and in definitely forming its interior surface.

1 have found it advantageous to subject the cylindrical body after contraction and elongation to a low heat treatment, between 200° C. and 400° C., such treatment doubtless relieving some interior strains but notably increasing the hardness and wearing qualities of the metal. The temperature to be employed will naturally vary with the nature of the metal; those I have instanced relate to ordinary commercial steel.

For the successful application of my method, it is necessary that the wall thickness of the cylindrical body under treatment should be sufficient to prevent the liability of the body to crumple instead of radially contracting under the influence of the fluid pressure applied to its exterior. The necessary wall thickness to obviate this liability will vary somewhat with the diameter of the cylindrical body under treatment but, as an example, I may say that with a steel tube of two inches internal diameter, the wall thickness should not be less than one thirty-second of an inch.

While my new method is, I believe, most usefully applied to the treatment of hollow steel bodies, I have also found it useful as applied to hollow bodies of brass and bronze and the improvement in the structure of the metal is noticeable with such metals, but while I believe such structural improvement will always follow my treatment, it will be understood that my invention has value as a forming process apart from such improvement.

Having now described my invention, what I claim as new and desire to secure by Letters Patent, is:

1. The method of changing the form and improving the metallic structure of tubular metal bodies of a generally cylindrical form which consists in securing such bodies in a high pressure container in such manner that the tubular body is free to expand longitudinally therein and subjecting the exterior cylindrical surface of the entire portion of the body to be operated upon to the simultaneous application of hydraulic pressure sufficient in amount to effect a permanent radial contraction and resultant simultaneous longitudinal elongation of said cylindrical body.

2. The method of claim 1 in which the deformation of the hollow body is aided by subjecting it to a longitudinally acting stretching force.

3. The method of claim 1 in which the deformation of the hollow body is limited by contracting it upon a mandrel.

4. Apparatus for radially contracting and longitudinally elongating hollow metal bodies of a generally cylindrical form consisting of a container, means for supporting a hollow metal body therein, including packings adapted to form fluid tight joints between the container and both ends of the hollow metal body and means for introducing fluid under pressure to said container at a point between the said packings.

5. Apparatus as called for in claim 4, having a mandrel supported thereon to give final form to the metal body.

6. Apparatus as called for in claim 4, in which a packing ring is anchored to an end 5 of the metal body so as to act as a piston imparting a longitudinal pull thereto.

FREDERICK C. LANGENBERG.
